UNITED STATES PATENT OFFICE.

JOHN H. JOHNSON, OF CHARLESTON, SOUTH CAROLINA, ASSIGNOR OF ONE-FOURTH TO
THOMAS MARKS, OF CHARLESTON, SOUTH CAROLINA.

DITCHING MACHINE.

Application filed June 14, 1922. Serial No. 568,102.

To all whom it may concern:

Be it known that I, JOHN H. JOHNSON, a citizen of the United States of America, residing at Charleston, in the county of 5 Charleston and State of South Carolina, have invented certain new and useful Improvements in Ditching Machines, of which the following is a specification.

The present invention relates to improvements 10 in ditching machines designed especially for use in connection with and carried by a railroad car, for plowing or excavating ditches alongside the tracks of the roadbed.

15 The primary object of the invention is the provision of a strong, durable, and easily manipulated ditching apparatus supported from the railroad car, and which may with facility be adjusted to various positions with 20 relation to the track and road bed for excavating or plowing alongside the track. The equipment of the invention is utilized in connection with standard flat cars, and the car of the work train carrying the plowing 25 apparatus is pulled by a locomotive. When not required for use, or while the car is in transit, or to permit passage of trains on another track, the ditching equipment may be folded onto its car in position within the 30 required limits of space for railway traffic. The invention consists in certain novel combinations and arrangements of parts as will be hereinafter more specifically set forth and claimed.

35 In the accompanying drawings one complete example of the physical embodiment of the invention is illustrated, wherein the parts are combined and arranged according to the best mode so far devised for the 40 practical application of the principles of the invention.

Figure 1 is a side view in elevation showing a railway flat car equipped with the ditching machine of the invention, and illustrating the use of three plows at the side of the car, together with a conveyer and car loader on a rear car, the latter being shown in dotted lines.

45 Figure 2 is a top plan view of the equipment of Fig. 1 illustrating a hinged plow frame at one side of the car, and two plows carried thereby.

Figure 3 is an enlarged end view showing the body of the car with two hinged plow frames, one in working position and the 55 other in folded position as when not in use.

Figure 4 is a detail sectional view at line 4-4 of Figure 2.

Figure 5 is a detail sectional view at line 5-5 of Figure 2.

Figure 6 is an enlarged detail view showing a portion of the side of a car, the corner of the plow frame being in section, and showing one of the corner brackets for supporting the hinged plow frame in working 65 position.

Figure 7 is a detail sectional view showing a plow frame or bracket-holder for the plow in its relation to the side or hinged frame, and means for vertically adjusting the plow 70 beam.

Figure 8 is a perspective view of a casting forming the bracket-holder for the plow, used in connection with the plow frame.

Figure 9 is a detail view of one of the 75 plowbeams illustrated for use in Figure 4, for supporting a plow in horizontal position when making lateral cuts or plowing in a band at the side of the track.

Figures 10, 11, and 12 respectively are 80 views showing an elevation, an edge view, and a sectional view (at line 12-12 Figure 10) of a front plow attachment for the car.

The ditching equipment of the invention is especially adapted for use in connection with 85 standard types of flat cars, one of which is illustrated in the drawings and provided with stringers 1, of I-beams, the car deck 2 and the usual wheels or trucks 3.

In adapting the flat car for use with the present equipment, a number of channel plates, as 4, are attached, as by rivets, beneath the car body, preferably at the center thereof, and extending longitudinally of the car. These plates are designed to accommodate a pair of plow frames as 5 and 6, and one located at each side of the car about midway thereof, and preferably rectangular in shape as shown. These plow frames may be made up of wood as shown and bound with steel plates to insure durability, or the frames may be made up of metal if desired. As shown in the drawings the rectangular plow frames are fashioned with wood inner and

outer bars 7 and 8 respectively, extending longitudinally of the car, front and rear end bars 9 extending transversely of the car, and diagonal braces 9', to form a rigid and well 5 braced plow frame at each side of the car.

The plow frames are designed to be supported in horizontal position and project laterally of the car when in use, but when not to be used they may be folded up on 10 hinges 10 which connect the plow frame with suitable portions of the car frame. At 11, four notches or recesses are provided in the deck of the car, two at each side, to accommodate the front and rear end beams 15 of the plow frame when the latter is folded over the car, as indicated in Figure 3.

In extended position, the plow frame is stayed or braced at front and rear by the use of brace rods 12, each provided with a 20 turnbuckle 13 for adjusting the length of the rod, and connected as by pins with eye plates or eye-mats 14 bolted to the plow frame and the car frame respectively.

At the front and rear ends, the inner corners of the plow frame are each supported in a supporting bracket 15 which is riveted to the side plate 4 on its exterior face, and the brackets are each fastened with an angular socket or hanger to receive and support 30 the corner of the plow frame when extended.

For raising and lowering the hinged plow frames or hinged wings of the car, means are provided on the deck of the car, and may 35 include bases or sockets 16 and 17 for the respective masts 18 and 19. These masts are of suitable construction and spaced at convenient positions along the center line of the car deck in order that connections may 40 be made to eye-bolts 20 or other fastening devices on the outer sides of the plow frames. The cables 21 are provided with the usual hoisting tackle and devices and supported from the masts so that by their 45 connection with the eye bolts 20, the cables may be wound or unwound on the winches designated by the numeral 22. These winches may be manually operated or operated by power from a suitable source, and 50 when actuated are designed to raise or permit the lowering of the plow frames in well known manner.

After being lowered to extended position, with their inner edges supported in the angular brackets 15, the brace rods 12 are coupled between the plow frame and car frame, and the cables 21 from the masts to the outer edges of the plow frames, all assist in holding the plow frame in rigid position.

60 The plow frames are designed to support one or more plow beams as 23 and 24, either of which may be used singly, or both of which may be used to cut or plow on parallel lines if desired. The plows 25 and 26

on the lower ends of the respective beams 23 65 and 24 may be of any standard or desired type and may vary according to the purpose or nature of the ditching operations.

The plow beams, and especially the beam 23, are suspended perpendicularly from the plow frames or side wings of the car, with the plows at the lower ends of these perpendicular beams in operative position with relation to the ground level. For this purpose cast metal bracket-holders are employed, which are somewhat of cruciform and adjustable on the side frame or plow frame. In Figure 8 wherein the bracket-holder is shown in perspective, it will be seen that the holder is fashioned with vertical guide walls 28 to form a rectangular guide groove for the plow beam 23, and that it also has angular, or horizontally extending clamp channel-flanges 29 to embrace the outer bar of the plow frame, to 85 which it may be bolted in position.

At the inner side of the bracket holder the walls 28 are extended to form webs or flanges 30, 30 having openings or apertures 31. Between these webs a rack wheel 32 is 90 journaled with its shaft 33 in the apertures, and the rack wheel or pinion 32 is located in position to mesh with the rack plate or rack bar 34 embedded in a groove provided therefor in the inner longitudinal face of the 95 plow beam. The rack pinion 32 may be retained in position by means of the pivoted pawl 35 which engages the teeth of the pinion in usual manner. Thus it will be apparent that the plow beam is supported in the vertical walls of the bracket-holder and may be moved therein by turning the shaft 33 of the pinion 32 to raise or permit lowering of the beam, and in this manner adjust the depth of the cut of the plow 25. When 105 so adjusted the plow beam and its plow are maintained in proper working position and fixed to the plow frame, which in turn is rigidly supported from the car.

The inner plow 26 and its beam 24 are 110 supported on a rock-beam 36, by a bracket-holder 27 similar to the bracket holder 27 for the outer plow. This rock beam is carried at the longitudinal center of the plow frame and extends longitudinally of the 115 plow frame, just above the latter. At its ends the rock beam is fashioned with a pair of trunnions or pins 38, which are journaled in bearings 39 at the front and rear ends of the plow frame, and the rock beam with its attached plow beam and plow, as 24 and 26 respectively, may be turned in these bearings to present the plow at various angles to the ground level for plowing or ditching as desired. Thus the plow 26 may be adjusted to angular position, and by means of the rack wheels 40 and pawls 41 at the 120 ends of the rock beam, the plow may be re-

tained in position for work. As before stated either of the plows 25 and 26, or both of them may be used if desired.

For making lateral cuts, or digging in the sides of a bank alongside the track, special plow racks 42 and 42' are employed. These racks are preferably placed at the center of the car and extend transversely thereof, the notches 43 of the racks facing in opposite directions toward the sides of the car. The plow beam 44 is placed in the desired plow rack, which is somewhat of U-shape in cross section, and the trunnion bar 45 at the end of the plow beam is engaged in a pair of notches 43. The plow-beam 44 carries a plow at its extreme outer end, designed to cut into the face of a bank, and it will be seen that at its inner end the plow beam is hinged by its trunnion bar in the notches 43. A mast 46, erected between the two plow-beam guides or racks 42 42' and provided with usual hoisting block and tackle may be utilized for raising or lowering the transversely extending plow beam 44. One beam may be used at a selected side of the car, or two may be used if desirable extending in opposite directions for cutting the face of a bank, and when not in use either or both of these beams may be turned up to anoperative position above the car deck, or if necessary such beams may readily be disengaged from their racks and laid upon the deck of the car.

For plowing or cutting in close to the ends of the track rails I may use a front plow as 47, located at the front end of the car, at either or both sides thereof. Such a plow may have a forward cutting edge 47' and is suspended by bars 48, which are riveted to the plow, from a horizontally extending hinge rod 49. The suspending bars are each fashioned with a suspending ear 50 on the hinge rod 49, and a tension spring 51 coiled about the hinge rod is designed to swing the plow upwardly on the hinge rod 49 as a center to remove the plow from working position. The hinge rod is supported on a hinge pin 52, vertically disposed at the side of the car and swiveled in perforated ears or eye-bolts 53 fixed to the car frame. A diagonal brace 54 is swiveled through its collar 53' on the hinge pin, and is connected to a collar 55 on the free end of the hinge rod. This the hinge rod, the hinge pin and the diagonal brace form a triangular plow frame which is swiveled or hinged on the side frame of the car, so that the plow when not in use may be turned up on its hinge rod, and the triangular frame swung around parallel with the side of the car carrying the plow with it where it will be out of the way. When extended for use, the front plow may be braced from the side of the car by brace rods 55' as shown in Figure 1, which rods

extend from the side of the car to the rear or inner side of the plow, and hold it against pressure from the front as the plow moves forward.

In Figure 1, a pair of cranes or derricks 56 and 57 are shown as erected at the ends of the flat car, which are designed for use in hoisting or lowering the loading mechanism shown in dotted lines. A scoop 58 is designed to gather the plowed dirt or soil which is received in the hopper or receiver 59 at the rear thereof. From the hopper the dirt is carried by an elevator 60 to the conveyer 61 supported alongside the dirt car 62 which is coupled to the car shown in full lines and carrying the plow equipment. Thus the plow or ditching car and the dirt or loading car may be pulled or pushed by a locomotive, the forward car for the purpose of excavating or plowing the dirt, and the rear car to load the material thereon, from whence it may later be dumped.

While I have shown and described the side wings or plow frames for use at one side of the car, it will be understood that the structure of the duplex frames is the same, and that one plow frame may be lowered to working position, or both frames may be used, when it is desired to form a ditch at both sides of the track.

Various changes and modifications may be made in the structures shown and describe, and other devices or accessories that may be necessary will of course be used, but such changes and alterations will be within the scope of my claims and will not depart from the spirit of my invention.

The several devices shown in the drawings are adapted for co-operation in the work of forming ditches, and some of the parts are interchangeable, as for instance the boms or beams 44 may be used to work at either side of the track in widening cuts, and the boom or booms may be stepped back or forward transversely of the car, within the length of the guides 42, and raised or lowered at the same time by cables and tackle or other hoisting mechanism including the mast 46 and winches.

The front plow 47 illustrated at one side of the car may also be utilized at the opposite side thereof for throwing dirt out from the ends of the ties of the roadbed, and it will be apparent that should the curved end 47' encounter an unusually long tie, or other irregularity, the resiliency of the spring 51 will take up the shock and return the plow to proper position after passing the obstruction.

Having thus fully described my invention, what I claim and desire to secure by Letters Patent is—

1. The combination with a supporting vehicle, of a longitudinally extending, hinged

side frame and means on the side of the car for supporting said frame in working position, means for raising and lowering said hinged frame, a bracket-holder longitudinally adjustable on said frame, and a vertically adjustable plow beam supported in said bracket-holder.

2. The combination with a railway car, 10 of a longitudinally extending side frame having hinges at the side of the car and means supported on said car for raising and lowering said frame, fixed brackets on the car for supporting said frame in working position, a longitudinally adjustable bracket-holder on said frame, and a plow beam vertically adjustable and supported in said bracket holder.

3. The combination with a railway car 20 and its longitudinally extending hinged plow frame, of a longitudinally extending rock bar, bearings on said frame for said bar, means for holding said bar in adjusted position, and a plow supported from said rock bar.

25 4. The combination with a railway car and its hinged side plow-frame, of a longi-

tudinally extending rock bar supported in said frame, a bracket-holder fixed to said rock bar, a plow beam supported in said bracket-holder, and a plow on the beam.

30

5. The combination with the hinged plow-frame of a rock bar having bearings therein, means for holding said rock bar in adjusted position, a bracket-holder fixed to said rock bar and movable therewith, a plow beam adjustable in said bracket-holder, and means for holding said plow beam in adjusted position.

35

6. The combination with the hinged plow frame, of a rock bar having bearings therein and a pawl and ratchet for holding said bar in adjusted position, a bracket-holder fixed to said rock bar and movable therewith, a plow beam having a rack bar and adjustably supported in said bracket holder, a rack- 45 pinion journaled in the bracket-holder engaging said rack bar, and means for holding the pinion in adjusted position.

40

In testimony whereof I have affixed my signature.

JOHN H. JOHNSON.
